FIG.10

FIG.11

FIG. 1 is a side elevational view of a windshield wiper blade unit showing our new design, the opposite side being a mirror image thereof;

FIG. 2 is a top plan view thereof;

FIG. 3 is a bottom plan view thereof;

FIGS. 4 and 5 are enlarged fragmentary side elevational views of the end portions thereof;

FIGS. 6 and 7 are enlarged fragmentary top plan views of the end portions thereof;

FIGS. 8 and 9 are enlarged fragmentary bottom plan views of the end portions thereof;

FIG. 10 is an enlarged end elevational view thereof; and

FIG. 11 is an end elevational view thereof opposite to that shown in FIG. 10.

The broken lines seen in FIG. 1 represent variable environmental structure which forms no part of the present design.

We claim:

The ornamental design for a windshield wiper blade unit, substantially as shown and described.
